BLANKET INSULATED REFRIGERATOR CAR

Gustav P. Torburn, Oakland, Calif.

Application March 13, 1936, Serial No. 68,619

6 Claims. (Cl. 105—423)

The present invention relates to refrigerator cars in which the walls, floor and roof are protected against entrance of heat by means of insulation applied in the form of felted or woven sheets or blankets.

Blanket insulation is more efficient than other forms, and is considerably cheaper and easier to install. Its use permits thinner and lighter walls, thereby saving space, material, and weight.

10 It has been used in refrigerator cars to some extent, but with indifferent success, the difficulty being that, in order to be most effective, it must be continuous, or as nearly so as possible, around the sides, ends, floor and roof of the car, and 15 must have a minimum number of fastening members extending through it. Under such conditions, which are necessary to proper efficiency of insulation, no successful and practicable means have heretofore been developed for holding the blanket insulation in place, and for connecting the inner and outer walls of the car together with sufficient strength and rigidity to withstand the 20 stresses of loading and traveling.

The principal object of the present invention 25 is to overcome the difficulties described above, viz.—to provide a construction in which the inner structure or lining of the car is as nearly as possible entirely surrounded by an unbroken layer of blanket insulation, and in which said lining, although independent, as respects its load-carrying function, of the outer walls of the car, and supported entirely by the under-frame and floor structure, is sufficiently attached to said outer walls to be adequately braced thereby.

30 A further object is to provide a construction in which the blanket insulation is compressed and supported at as few points as are necessary to keep it from shifting, and in which a minimum number of connecting members, such as bolts, screws and nails, extend between the lining and the outer frame, such connecting members as are necessarily employed terminating short of the inner and outer surfaces and their ends being insulated to prevent conduction of heat.

35 Still further objects are to provide a car having a wooden lining and a steel outer shell, which is so well insulated as to be superior in efficiency to the more usual all-wood structure; to provide improved construction whereby the inside lining 40 supports the inner ceiling and its insulation, entirely free from the outer steel roof; and to provide for extending the blanket insulation around the upper corners of the car, where the roof meets the walls, without interruption and without joints at said corners.

These and other objects and advantages of the invention will be brought out more fully in the following specification, which should be read with the understanding that the form, construction and arrangement of the several parts described and illustrated may be varied without departing from the spirit of the invention as defined in the appended claims.

Reference will be made to the accompanying drawings, wherein

10 Fig. 1 is a transverse section through a refrigerator car embodying a preferred form of the invention.

Fig. 2 is a broken plan view with the outer roof removed, showing one method of folding the 15 blanket insulation at the corners.

Fig. 3 is a broken plan view similar to Fig. 2, showing another method of folding the blanket insulation.

Fig. 4 is a vertical sectional detail of an upper 20 corner, taken on the line 4—4 of Fig. 2.

Fig. 5 is a vertical sectional detail showing the attachment of one of the ceiling carlines to the upper side belt rail.

Fig. 6 is a horizontal section of one end portion 25 of the car.

Fig. 7 is a vertical sectional detail of the roof and side wall lining, taken on the line 7—7 of Fig. 1.

30 In the drawings the reference numeral 8 designates the longitudinal central member of the under-frame of the car, and 8a are the transverse members thereof. At the outer ends of said transverse members 8a are longitudinal side angle members 8b extending the full length of the car, 35 to which the lower edges of the steel side sheathing plates 9 are riveted. Longitudinal angle members 10 are supported by suitably spaced brackets 11. The angle members 10 and wooden stringers 12, resting upon the transverse members 8a, support the wooden sub-floor 13. Longitudinal wooden spacers 14 are laid upon the sub-floor, some distance in from its side edges, and are bolted down to the angle members 10 by bolts 15, one of which is shown at the left in 40 Fig. 1. The heads of these bolts are deeply countersunk, as shown.

45 Two or more layers 16 of blanket insulation of any suitable and well known type are laid upon the sub-floor 13, between the spacers 14, with 50 their edges turned up against said spacers, as shown at 17. Wooden nailing cleats 18 are laid at suitable intervals above each layer to keep them from shifting and to support the inner wood floor 19, which is laid across on top of the spacers 55

14 and nailing cleats 18, and is covered, as usual, with a waterproof lining 20.

The steel side sheathing plates 9 extend upward almost to the roof of the car, and are reinforced by vertical Z bars 9a secured to their inner faces as shown in Fig. 6. Fig. 1 shows, at the left, a section of the solid portion of the side wall, whereas at the right is shown a door to be described later. Outer horizontal belt rails 10 21, 22 and 23 are secured, by any means not shown, to the inside of the side plates 9, and extend between the vertical Z bars 9a, except where the door interrupts them. A plurality of layers, preferably three, of blanket insulation 15 24 are positioned vertically against the outer belt rails, and are clamped between them and inner belt rails 25, 26 and 27 for support and to prevent shifting. Bolts 28 extend through both inner and outer belt rails to clamp them upon the 20 insulation. Both ends of these bolts are deeply countersunk, and the sockets in which their heads and nuts rest should be filled with some plastic insulating material. The inner lining 29 of the wall consists of wooden boards, preferably with 25 tongue and groove joints, set vertically, as shown in Fig. 7, instead of horizontally as is the usual practice. The lining 29 is nailed to the inner belt rails. The bottom inner belt rail 25 rests upon the inner floor 19, and is preferably chamfered, as at 30, to receive the ends of the lining 29. Ply-wood sheets may be used for the lining 29 instead of tongue and groove boards, the essential feature being that said lining must have sufficient compressive strength, in the vertical 35 direction, to support the weight of the ceiling structure, as described hereinafter.

It should be noted that the bolts 28 do not extend through either the outside steel sheathing plate 9 or the lining 29, and do not even contact 40 the surfaces thereof, so that there is no direct metallic path from outside to inside through which heat might enter by conduction.

The usual floor racks 31, for supporting the lading, are provided with hinged brackets, one of 45 which is shown at 32, bolted to the bottom belt rails. These bolts, like the bolts 28, do not extend either to or through the outer plate 9.

The ceiling structure, which is independent of the outer steel roof and is supported entirely by 50 the wall lining 29, comprises spaced transverse carlines 33, preferably wood, extending across between the upper inside belt rails 27, resting in notches 33a therein, and secured thereto by angle brackets 34 and bolts 35 (see Fig. 5). These carlines 33 also rest upon the upper edge of the side lining 29. The wooden ceiling lining 36, Figs. 1 and 7, is nailed to the under sides of the carlines 33, and a layer of rigid insulating board 37 is laid upon and nailed to their upper sides. 55 Molding strips 38 may be used if desired, at the corners between the wall and ceiling lining.

The wall insulation 24 is extended up about a foot above the upper belt rails 27, and its free upper edges are bent over horizontally, as shown 60 at 24a, on top of the rigid ceiling insulation 37, so that no joint occurs in said blanket insulation at the upper corner of the car. Moreover, the several layers of said blanket insulation are extended to different heights, so that, when bent 65 over, their edges are staggered, as shown at 24b, in Fig. 1. Between the edges of the bent over portions 24a of the side insulation are laid horizontal layers 39 of similar blanket insulation, resting upon the rigid insulation 37 and held between it and the steel roof 40 to prevent shifting. 70

The upper edges of the steel side sheathing plates 9 have longitudinal stiffening Z-bar members 41 secured to them, and to these is secured the steel roof 40 by means of intervening angle members 42. The roof 40 is of ordinary construction, reinforced by transverse ribs, one of which is shown at 43. It rests entirely on the steel side sheathing plates 9, and is independent of the ceiling carlines 33 and insulation 39. 75

If the particular blanket insulation used is heavy and thick, it must be mitered at the corners of the ceiling where it is folded over, as shown at 44 in Fig. 2. If it is thinner, and space will permit, it can be folded over in square corners, as shown at 44a in Fig. 3. The effect is the same in either case, viz:—that the side insulation is carried continuously up and around the angle between the wall and the ceiling, so that such joints as are unavoidable, as shown at 24b in Fig. 1, occur in the horizontal ceiling portion, 20 where they are less likely to spread apart than if they were located at the corner or in the vertical portion. Moreover, these joints 24b are staggered as between the several layers, so that there can be no direct opening through the entire body 25 of insulation at any point.

The wall insulation is continuous also at the vertical corners of the car, as shown in Fig. 6. Each layer 24 is a continuous blanket extending from the door post 45 on one side of the car, 30 to and around the end and back to the door post 45a on the other side, the ends of said blankets being clamped between nailing cleats 45b at said door posts. Thus there are no joints in the side wall insulation, except where necessitated by the 35 framing of the doors. Moreover, there are very few vertical clamping or nailing strips in the side walls between the insulation 24 and the lining 29, the only such strips being the cleats 45b at the door posts and similar cleats 45c at the 40 corners of the car and at the ends of the ice tank bulkhead 29a. The necessity for more frequent vertical nailing cleats is obviated by the solid steel outside plates 9 and the vertical arrangement of the lining boards 29. Therefore the 45 insulation is compressed only along the three horizontal belt rails and the few vertical cleats 45b and 45c, thus providing maximum effectiveness.

The construction of the end walls, shown in 50 Fig. 6 and in part in Fig. 4, is substantially the same as that of the side walls, and need not be described in detail. Horizontal nailing cleats 23a and 27a correspond in function and approximate position to the side belt rails 23 and 27. The 55 outside end shell is a steel plate 9b. Roof hatches 46 may be constructed in any desired manner, preferably with a woodframe 46a supported by the carlines 33, and a steel flange 40a secured to the roof 40 and extending into the wood frame 46a 60 as shown.

The framing of the door openings require the interruption of the insulation. At said doors, as shown at the right in Fig. 1, the three outer belt rails 21, 22 and 23 are interrupted, and also the 65 lower and middle inside belt rails 25 and 26. The upper inside belt rail 27, however, runs through above the door framing, thus providing continuous support for the ceiling carlines 33. The door frame comprises an outer wooden sill 47 which 70 fills the space between the side sheathing plate 9 and the spacer 14, and which is rabbeted to receive a reinforcing angle member 48 attached to said side sheathing plate 9, which is itself formed with a flange 49 extending over said sill 47. A 75

composition threshold plate 50, of usual type, overlies the sill 47 and the edge of the floor 49, and an inner sill 51 overlaps the inner edge of said plate. A gasket 52 is provided between the inner sill 51 and the door.

At the top of the door opening is a wooden lintel 53 secured to the side plate 9 by an angle member 54 and bolts 55. The lintel lies immediately under the belt rail 27 and reinforces it across the door opening, and also provides support for the lining 29 at this point. The blanket insulation above the door opening consists of three strips 24c, matching the ceiling blankets 39 with staggered joints 24b. These strips 24c extend around the horizontal corner between the ceiling and the side wall over the door opening, as shown, and have their lower edges clamped between a flange of the lintel 53 and the belt rail 27.

The door itself, which is hung in any suitable manner, not shown, comprises a rectangular wood frame 56 to which an outside steel plate 57 is secured by means of angle members 58 and bolts 59, said bolts preferably extending through the frame 56 in a direction parallel to the surface of the plate 57, as shown, rather than perpendicular to it, in order to minimize conduction of heat. The heads of all bolts used around the door are deeply countersunk and should be covered with plastic insulation. A plurality of layers of blanket insulation 60 are laid inside the steel plate 57 of the door, and their edges are turned inwardly, as at 61, and clamped against the frame 56 by nailing cleats 62. The wood lining 63 is nailed to the inside of the frame 56.

It will be seen from the foregoing that the construction described provides a continuous blanket insulation around the entire car, interrupted only at the door frames and at the lower corners where the inner floor is supported on the spacers 14. At these points the use of wooden framing members reduces heat conduction to a minimum, wood itself having good insulating properties. Moreover, the area of these regions where the blanket insulation is interrupted is reduced to a minimum, especially along the lower corners, by extending said insulation down to the sub-floor 18, as shown in Fig. 1, causing it to overlap the edges of the inner floor.

The continuity of the blanket insulation, particularly around the upper corners of the car, is made possible by the use of a steel outer shell for the entire car, and by making the lining as a separate structure whose weight is supported entirely by the under-frame and floor, and which carries the inner ceiling structure, and its insulation independent of the outer roof. The connections between the inner and outer belt rails 22 and 26, and 23 and 27, are for insulation fastening purposes only. The weight of the ceiling structure and its insulation is borne by the vertical compressive strength of lining boarding 28 directly from the lower belt rail 25, which rests upon the solid floor structure. This construction permits the blanket insulation to be carried around the upper corners and into the ceiling structure, which arrangement eliminates all joints in the insulation at the corners and in the vertical walls, and brings them into the ceiling where they are less liable to spread apart.

The described construction also provides dead air spaces in the walls, floor, and ceiling, thereby increasing the insulating effect; permits the least possible compression of the blanket insulation; and enables all connecting bolts running through the insulation to be terminated short of either

the outside shell or inside lining, or both, thereby minimizing conduction of heat. Finally, the use of a steel shell and roof, with a wood lining and blanket insulation, permits thinner walls for equivalent insulating effect, thereby saving space and weight.

I claim:

1. In a refrigerator car, an outer shell having walls and a roof supported thereby; a lining spaced within said shell and having walls and a ceiling supported by said lining walls; blanket insulation within the spaces between the shell walls and the lining walls, said insulation extending continuously without horizontal joints from the floor of the car to and above said ceiling and being folded over horizontally to lie on top of said ceiling; and additional blanket insulation in the space between said ceiling and said roof, extending between the folded edges of said wall insulation, the joints between said wall insulation and said ceiling insulation being in the horizontal space between the ceiling and the roof.

2. In a refrigerator car, an outer shell having walls and a roof supported thereby; a lining spaced within said shell and having walls and a ceiling supported by said lining walls; a plurality of insulating blankets within the spaces between the shell walls and the lining walls, said blankets extending continuously without horizontal joints from the floor of the car to and above said ceiling and being folded horizontally over said ceiling; and additional insulating blankets resting upon said ceiling and filling the space between the folded edges of said wall blankets, said blankets being of different widths whereby the joints between the wall blankets and the ceiling blankets are staggered, all said joints being between the ceiling and the roof.

3. In a refrigerator car having spaced inner and outer side and end walls, a roof supported by the outer walls, and a ceiling supported by the inner walls and spaced below said roof; insulation between said inner and outer walls and said ceiling and said roof, said insulation comprising a blanket extending continuously from a point in one side wall to and through one end wall to a point in the other side wall, said blanket also extending continuously from the bottoms of the walls to and around the corners between said walls and the ceiling, the upper edge portion of said blanket being folded over horizontally to lie upon said ceiling, whereby there are no joints in said blanket at either the vertical corners between the side and end walls or the horizontal corners between the walls and the roof.

4. In a refrigerator car having spaced inner and outer side and end walls, a roof supported by the outer walls, and a ceiling supported by the inner walls and spaced below said roof; insulation between said inner and outer walls and said ceiling and said roof, said insulation comprising a blanket extending continuously from a point in one side wall to and through one end wall to a point in the other side wall, said blanket also extending continuously from the bottoms of the walls to and around the upper corners of the car, and another blanket lying upon said ceiling and filling the space between the folded edges of the wall blanket, whereby there are no horizontal joints in the wall insulation, and no joints whatever at either the vertical or upper horizontal corners of the car.

5. In a refrigerator car, a metal outer shell having walls and a roof supported thereby; non-

metallic lining walls spaced within said shell walls; carlines extending across above said lining walls and supported thereby in spaced relation below said roof; a ceiling lining secured to the under sides of said carlines; a layer of rigid insulation resting upon the upper sides of said carlines; and blanket insulation within the space between the shell and the lining, said blanket insulation extending around the corners between the walls and the ceiling, and having a horizontal portion resting upon and wholly supported by said rigid insulation.

6. In a refrigerator car, a metal outer shell having walls and a roof supported thereby; non-metallic lining walls spaced within said shell walls; carlines extending across above said lining walls and supported thereby in spaced relation below said roof; a ceiling lining secured to the under sides of said carlines; a layer of rigid insulation resting upon the upper sides of said carlines; and blanket insulation within the space between the shell walls and the lining walls, the upper edge portions of said blankets extending around the corners between the walls and the ceiling and being bent over the edge portions of said rigid insulation; and another insulating blanket lying upon said rigid insulation and extending between the bent over edges of the first mentioned blankets, whereby the entire lining structure of the car is covered by blanket insulation, and the only joints therein are positioned in the horizontal portion thereof above the ceiling.

tion below said roof; a ceiling lining secured to the under sides of said carlines; a layer of rigid insulation resting upon the upper sides of said carlines; insulating blankets within the spaces between the shell walls and the lining walls, the upper edge portions of said blankets extending around the corners between the walls and the ceiling and being bent over the edge portions of said rigid insulation; and another insulating blanket lying upon said rigid insulation and extending between the bent over edges of the first mentioned blankets, whereby the entire lining structure of the car is covered by blanket insulation, and the only joints therein are positioned in the horizontal portion thereof above the ceiling.

GUSTAV P. TORBURN.
